(57) **CLAIM**

The ornamental design for a wheel of baby carriage as shown and described.

DESCRIPTION

FIG. 1 is a perspective view of a wheel of baby carriage showing my new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof; and,

FIG. 8 is a section view thereof.

The broken lines shown in the drawings depict portions of a wheel of baby carriage that are not considered part of the claimed design.

1 Claim, 8 Drawing Sheets
